UNITED STATES PATENT OFFICE

136,904

DESIGN FOR A HEAT TRANSFER UNIT

Newenham A. Gray, Wausau, Wis., assignor to
D. J. Murray Manufacturing Co., Wausau, Wis.,
a corporation of Wisconsin

Application June 7, 1943, Serial No. 110,387

Term of patent 14 years

To all whom it may concern:

Be it known that I, Newenham A. Gray, a subject of the Empire of Great Britain, residing at Wausau, in the county of Marathon and State of Wisconsin, have invented a new, original, and ornamental Design for a Heat Transfer Unit, of which the following is a specification, reference being had to the accompanying drawing, forming part thereof.

In the drawing:

Fig. 1 is an edge view of a heat transfer unit embodying my new design;

Fig. 2 is a side view of the heat transfer unit of Fig. 1; and

Fig. 3 is a transverse section through the medial portion of the heat transfer unit, looking toward either end thereof.

All parts of the elongated medial portion of the heat transfer unit have approximately the same elliptical transverse cross-section, and both of the opposite edge views are the same as that shown in Fig. 1, while both of the opposite side views are likewise the same as that shown in Fig. 2.

I claim:

The ornamental design for a heat transfer unit, approximately as shown and described.

NEWENHAM A. GRAY.
